GOODYEAR'S METALLIC RUBBER SHOE COMPANY, A CORPORATION OF CON-
NECTICUT.

RUBBER BOOT AND METHOD OF MANUFACTURING THE SAME UNDER DIFFERENTIAL OF PRESSURES.

1,368,682.

Specification of Letters Patent. Patented Feb. 15, 1921.

Application filed January 20, 1920. Serial No. 352,667.

To all whom it may concern:

Be it known that we, JOHN ALM and JAMES HUGHES, citizens of the United States, both residing at Naugatuck, county of New Haven, and State of Connecticut, have invented certain new and useful Improvements in Rubber Boots and Methods of Manufacturing the Same Under Differential of Pressures, of which the following is

10 a full, clear, and exact description.

This invention relates to rubber boots and a method of manufacturing the same under differential of pressures.

In the manufacture of rubber boots under the so-called "differential method", the numerous parts are assembled upon a last, being joined together by the adhesion of certain of their interengaging rubber or rubberized surfaces, the parts being rolled down upon the last so as to conform with the contour of the latter. A hollow perforated last is generally employed in the method, so as to bring the interior of the last into communication with the fabric lining of the boot, the perforations being preferably formed at the sole portion of the last. At a stage in the manufacture of the boot, and generally during the application of heat thereto to effect vulcanization, the exterior of the boot is subjected to a fluid pressure greater than that of the pressure within the interior of the last and boot, to remove any fluid entrapped between or within the assembled parts of the boot, the effect of this step being not only to solidify and compact the boot structure, and therefore prevent porosity and ply separation, but incidentally to cause the boot to closely hug the last. Inasmuch as the lining of the boot consists of a wear-resisting layer of heavy fabric, rubberized on its interior to effect a permanent bond with the rubber vamp, counter or upper, as the case may be, the effect of the differential of pressures during the heat of vulcanization may force the rubber coating of the lining through the latter and into contact with the last. In such case when vulcanization is completed, the adhesion between the lining and the last greatly resists the stripping of the boot from the last. The use of talc, soap stone, mica, aluminum flake, applied either to the last or the lining as a

powder or paint to overcome this problem is not desirable for several reasons, among which is the fact that such materials tend to work into the seams and prevent secure joints being made between the parts of the boot, and the further fact that such materials tend to render the lining non-porous and thus resist the differential treatment.

By our invention we overcome the problem in question by interposing between the lining of the boot and the last, a porous material which generally will become incorporated into the boot structure by adhesion to the lining, but which may not be strain resisting or possess any functional action in the boot, and which will resist the passage of rubber from the lining to the last, and thus will act as a guard or protection for the latter. The material is preferably a cheap, light-woven fabric which is sufficiently strong to withstand the strain necessary to pull it from the surface of the lining, when desired, and yet which may possess such slight resistance to wear, that, when not removed from the boot after vulcanization, it will rapidly disintegrate and expose the wear-resisting lining beneath it. In some cases, the protecting material may be placed upon the last prior to the assembly of the parts of the boot thereon, but the material is preferably applied directly to the boot lining prior to the assembly of the latter upon the last.

For a more complete understanding of the preferred method, reference is made to the drawings, in which:

Figure 1 is a plan view of the leg portion of a boot.

Fig. 2 is a plan view of the vamp.

Fig. 3 is an elevation partly in section of the boot in assembled condition upon a last, the latter being provided with means for reducing the pressure within the last.

In the preferred method, the leg portion of the boot is built up by superposing upon the outer ply 1 of sheeted rubber, an inner ply of heavy strain-resisting rubberized fabric 2, and upon the latter a wear-resisting lining piece 3 of rubberized fabric. Upon the lining piece 3 we place the protecting sheet 4, which may be of cheap fabric possessing the qualities hereinbefore set forth,

- such as cheese-cloth. When the lining 3 is rubberized on both sides, the protecting sheet 4 may be assembled in the leg structure so as to be held in place during manipulation. 5 of the latter, by passing the leg structure through a warm calender. And where the lining fabric is frictioned only on the side in contact with the strain resisting sheet 2, its margin or its entire surface may be covered with sufficient cement to hold the sheet in place during the assembly of the boot. The vamp, built up in like manner, comprises the sheeted-rubber vamp piece 5, the rubberized fabric lining 6, which acts as a 10 strain and wear-resisting member, and the protecting sheet 7. It will be understood that in the assembly of the parts upon the last, any customary or desired method of procedure may be employed.
- 20 In the boot shown in the drawing, the leg structure is applied to the last and its margins 8 are overlapped and united. Next the margins 9 are turned in upon an insole (not shown). The vamp is then placed in position, its marginal portions 10 being lapped upon the leg portion and its margins 11 being turned in upon the insole. Next the quarter ply 12 of sheeted rubber is placed in position, as shown in Fig. 3, and is turned upon the insole. When desired, the protecting sheet may be coextensive with the lining so as to be turned in with the latter upon the insole. The assembly of the outsoles, including the smooth sole 13 and tap sole 14, and the heel 15, then takes place in the customary manner. It will thus be seen that the protecting sheet is disposed intermediate the lining and the last through out the interior of the boot.
- 40 The last is provided with an aperture 16 to receive the nipple 17 of a pipe 18, which in practice may be connected with a suction device for producing a reduced pressure, that is to say, a partial vacuum, within the 45 interior of the boot.
- While we preferably employ a light fabric as the protecting sheet or false lining, the material may be any other thin, flexible porous material, fibrous or non-fibrous in its character. In some cases the material may be placed upon the last prior to the assembly of the boot, but it is preferably applied directly to the lining before the latter is lasted with the remaining elements of the 55 boot.
- In the vulcanizing operation, the differential of pressure will, as hereinbefore stated, force the boot firmly in contact with the walls of the last, and rubber will be drawn 60 toward the last from the rubberized lining. The protecting sheet, or false lining, however, will receive the rubber and therefore adhesion between the boot and the last will be prevented.
- 65 In a boot manufactured under the "dif-
- ferential" process, the various layers of rubber and fabric adhere to each other with much greater tenacity than is the case with a boot made by the old process, in which the adhesion of the various layers is secured by 70 pressure applied by the manipulation of a hand roller. In a boot made by the old method, the fabric plies strip from each other with varying or unequal resistance, showing that the adhesion between any two 75 opposed plies or layers is not of the uniform tenacity. The characteristic of a boot manufactured under the "differential" process is that the adhesion between any two opposed layers is of the same tenacity through 80 out.
- By our invention we are able to produce a novel boot by coating the wear-resisting lining with rubber on both surfaces, and by vulcanizing these two surfaces simultaneously with the remaining parts of the boot, and under a differential of pressures, the protecting sheet or false lining being preferably stripped from the interior of the boot after vulcanization of the latter. Such a 90 boot has great utility, in that it possesses the characteristics of a boot vulcanized under a differential of pressures and includes a uniform vulcanized-rubber coating upon the exposed surface of the lining, which prevents the rotting of the latter when the boot is subjected to severe use. The boot is markedly superior to one in which the exposed lining coat is applied after vulcanization of 100 the boot, in which case the boot must withstand a second cure with the consequent weakening of its structure. Whereas in our boot the two rubber surfaces of the lining possess identical characteristics, in the two-cure boot the inner rubber surface will be 105 different from that of the exposed rubber surface.
- Having thus described our invention, what we claim and desire to protect by Letters Patent is:
1. In the manufacture of a boot comprising a sheeted rubber exterior and a rubberized fabric wear-resisting lining, assembling the boot upon a last and placing a flexible sheet intermediate the boot lining and the last, and vulcanizing the boot under a differential of pressures, the greater pressure being applied to the exterior of the boot.
2. In the manufacture of a boot comprising an exterior of sheeted rubber and a wear-resisting lining of rubberized fabric, assembling the boot upon a pervious last and placing a false lining intermediate the boot lining and the last, and adapted to permit the passage of fluids from the boot to the interior of the last and to impede the passage of rubber from the lining to the last, and the step of vulcanizing the boot under a differential of pressures, the greater pressure being applied to the exterior of the boot.

3. The method of making rubber foot wear having a coating of rubber on the interior of the strain resisting lining, comprising the steps of building up the article of 5 several plies of sheeted material including a strain resisting lining of rubberized fabric and placing said plies on a last, together with a parting sheet interposed between the article and the last, and then vulcanizing the 10 article under pressure and maintaining a greater pressure on the exterior thereof to press the different plies toward each other and toward the last.

4. The method of making rubber boots 15 having a coating of rubber on the interior of the strain resisting lining, comprising the steps of assembling the boot upon a previous last and placing a false lining of fabric between the boot parts and the last, 20 and then vulcanizing the boot under a differential of pressure, the greater pressure being applied to the exterior of the boot.

5. In the manufacture of a boot comprising a sheeted rubber exterior and a rubberized fabric wear-resisting lining, assembling 25

the boot upon a pervious last and placing a flexible porous sheet intermediate the boot lining and the last, vulcanizing the boot under a differential of pressures; the greater pressure being applied to the exterior of the 30 boot so that rubber from the lining will be drawn against said sheet, removing the boot from the last, and stripping the sheet from the lining.

6. A vulcanized rubber boot composed of 35 layers of vulcanized rubber and fabric in which the adhesion between opposed layers is of the same tenacity throughout, and including a fabric lining having both of its surfaces coated with rubber vulcanized 40 simultaneously.

7. A rubber boot comprising an exterior of sheeted rubber, a wear-resisting rubberized fabric lining, and a false porous lining 45 superposed upon the latter.

Signed at Naugatuck, Connecticut, this 12 day of January, 1920.

JOHN ALM.
JAMES HUGHES.
